[57] CLAIM

The ornamental design for a farrowing crate, substantially as shown and described.

DESCRIPTION

FIG. 1 is a perspective view of the farrowing crate showing my new design;

FIG. 2 is a bottom plan view thereof;

FIG. 3 is a top plan view thereof;

FIG. 4 is a front view thereof;

FIG. 5 is a right side view, wherein the left side is a mirror image thereof; and

FIG. 6 is a rear view thereof.
